UNITED STATES PATENT OFFICE.

JACOB RITTER, OF FAR ROCKAWAY, NEW YORK.

BAG.

Application filed January 16, 1925. Serial No. 2,741.

To all whom it may concern:

Be it known that I, JACOB RITTER, a citizen of the United States, and a resident of Far Rockaway, county of Queens, and State 5 of New York, have invented certain new and useful Improvements in Bags, of which the following is a specification.

This invention relates to bags, and particularly, ladies' hand bags, and the general 10 object of the invention is to provide a securing means which is, under normal circumstances, concealed, but which may be readily operated to open the bag.

A further object is to provide a bag which 15 has an invisible, collapsible frame combined with the concealed securing means.

Further objects will appear from the description to follow and embodiments of the invention will be shown in the accompanying 20 drawings, and the invention will be hereinafter described and finally pointed out in the claims.

In the accompanying drawings:—

Figure 1 is a perspective view of one embodiment of my invention;

Figure 2 is a section taken on line 2—2 of Figure 3;

Figure 3 is a perspective view of a modified form of my invention;

Figure 4 is a sectional view of still another modified form;

Figure 5 is a sectional view of still another modified form;

Figure 6 is a perspective view of another embodiment;

Figure 7 is a perspective view of another embodiment, and

Figure 8 is a vertical section taken on line 8—8 of Figure 7.

Similar character references indicate corresponding parts throughout the various views. While the bag is preferably made of textile or leather material, the sectional views show the parts as plain lines in order 40 to avoid confusion in the representations.

Referring to the drawings and more particularly to Figures 1 and 2, there is shown a bag having an invisible, collapsible frame member which is concealed and which normally holds the bag in closed position. When the opening of the bag is extended, or opened this concealed frame holds the same open. The bag itself may be of any shape, as indicated by 10 and it has at its upper portion forming the opening of the bag hems or loop portions 11 which surround and enclose

the metallic frame 12. This metallic frame is hinged at 13 and 14 and also at 15 and 16. The sides of the bag are gathered at the lower portion of the frame, and, acting as 60 gussets, gives additional support and eliminates pulling and sagging. Extending beyond the textile covering of the invisible frame 12 are upwardly extending members made of textile material, indicated by 17, 65 which extend above and these materials are made relatively stiff though flexible, being made of superimposed textile materials so as to give with the opening or closing of the bag but retain their positions in conformity 70 with the opening and closing of the invisible collapsible frame. A suitable closing device may be provided, as indicated by the snap members 18 and 18^a in Figure 4, or by another form 19, in Figure 5, and then a covering flap 20 secured at 21 having a snap fastener 22 which may be provided so as to give an artistic appearance to the bag, as shown in perspective view in Figure 6.

Preferably, however, I provide instead of 80 the fastening devices 18, 18^a and 19, in Figures 4 and 5, a concealed hookless fastener as shown in Figures 1, 3, 7 and 8, which may be readily closed or opened by the movement of the sliding member 23. The structure 85 of these fastening devices is shown in U. S. Letters Patent No. 1,322,650, and I make no claim to the structure thereof as my invention, claiming however the cooperation with and combination of this particular fastening 90 device, the specific arrangement and locality of which enables a very efficient bag to be produced. The members holding these hookless fasteners are indicated in Figure 3 in perspective by the character 25, and shown 95 in the section, in Figure 2, the members supporting the metallic fasteners being arranged on the textile loop above the invisible frame and at the lower portion of the members 17. By this arrangement when the bag 100 is closed these extending members 17 being held by the loops applied thereto have a tendency to hide this hookless fastening device from view.

In Figures 7 and 8 I have shown this 105 fastening device 25 applied to a bag but these embodiments do not contain the invisible collapsible frame and in order to provide an efficient bag the inner lining 26 extends to the lower portion 27 of the hookless fastener and the two members 17 and 17^a are capable of spreading action, the

lower portion of the member 17 being secured to and in continuation with the bag 10 itself. Between the two members 17 and 17^a and secured to their upper edges is 5 stiffening member 24 of cardboard or other suitable material. This member extends downwardly and has its lower edge free between the lower edges of members 17 and 17^a so that the lower portions of all of these 10 members are capable of independent movement. By this arrangement I provide a gap portion 27 between the member 26 and bag 10 and give a certain flexibility to the movement of the parts in that while the bag is 15 closed the portions 26 act as a closure top to the contents of the bag, whereas when the bag is opened these parts 26 fall in line with the outer covering of the bag.

Among the advantages, is the provision of 20 a bag that gives and provides a roomy construction. The upwardly extending members, being secured at their upper edges only, permit the fasteners to be drawn together without drawing upon the outer member 25 and bag material, and the hookless metallic fasteners and sliding member provides fastening means for the bag which prevents the contents from falling out or the bag from opening without the knowledge of the 30 owner. The invisible collapsible frame in the upper portion of the bag adds strength to the bag and prevents the breaking of the bag and fastening means.

Another advantage is the provision of a 35 bag which can be quickly opened, and due to the construction of the upper portion thereof, will remain in open position or in closed position owing to that tendency offered by the collapsible frame and stiffening 40 in the upwardly extending members 17.

Other advantages appear in the ready opening of the bag and the ready closing of the same, no part of the fastening device being in the way of the use of the bag.

45 Further advantages of the constructions of the embodiments disclosed will readily appear to users of such bags and those skilled in the art.

Having shown and described preferred 50 embodiments of various features of my invention, it is to be understood nevertheless that the bag may also be produced in various other alternative forms. Accordingly, I reserve the privilege of resorting to all such 55 legitimate changes in form, proportion, and arrangement of the parts as may be fairly considered within the spirit and scope of the invention as set forth in the following claims.

60 By virtue of the fact that the members 17 and 17^a are held together at their upper ends and preferably there secured to the stiffener 24 as indicated at 24^a, the bag when it is filled, permits an expanding movement of 65 the members 17 and 17^a in respect to the

stiffening member 24. In certain cases the stiffener 24 follows either the member 17 or the member 17^a. By virtue of the considerable contents in the bag, the parts 17 and 17^a spreading out or expanding, permit 70 the bag to take care of such excessive contents and the strains and stresses instead of being localized at the stiffening frame and closure as is the case in bags heretofore in use, is not localized but is taken care of by 75 the spreading action of the parts 17 and 17^a.

I claim:

1. A bag comprising a container open at its top, side portions on the bag extending upwardly beyond the open top, a plurality of hingedly connected frame sections secured to the bag and spaced slightly below the open top thereof for distending and collapsing the open top, and a hookless fastener having its side members secured to the open 80 top of the bag and spaced above the frame sections and its sliding member operating between said upwardly extending side portion of the bag, said hookless fastener adapted to close the open top of the bag and yieldingly hold the frame sections collapsed.

2. A bag comprising an outer container having an opening at its top, a lining member within the container in which articles are to be received, upwardly extending portions of the bag arranged on either side 95 above the opening at the top of the container, said portions each having an outer member secured to the outer container and an inner portion secured at its upper edge 100 to the upper edge of the outer member and its lower edge to the lining member within the container, and a stiffening member secured between the upper edges of said inner and outer members of the upwardly extending 105 portion of the bag and extending between the lower edges of said portion.

3. A bag comprising an outer container having an opening at its top, a lining member within the container in which articles are to be received, upwardly extending portions of the bag arranged on either side above the opening at the top of the container, said portions each having an outer member secured to the outer container and 110 an inner portion secured at its upper edge to the upper edge of the outer member and its lower edge to the lining member within the container, a stiffening member secured between the upper edges of said inner and outer members of the upwardly extending 115 portion of the bag and extending between the lower edges of said portion, a hookless fastener having its side members secured to the lower edges of the inner members of the 120 upwardly extending portions of the bag, and a sliding member on said fastener members having an operating member between said upwardly extending portions of the bag.

4. A bag comprising an outer container having an opening at its top, a lining member within the container in which articles are to be received, upwardly extending portions of the bag arranged on either side above the opening at the top of the container, said portions each having an outer member secured to the outer container and an inner portion secured at its upper edge to the upper edge of the outer member and its lower edge to the lining member within the container, a stiffening member secured between the upper edges of said inner and outer members of the upwardly extending portion of the bag and extending between the lower edges of said portion, and a collapsible frame comprising hinged sections concealed between said outer container and inner lining member below the opening of the container adapted to maintain the bag in open or closed position.
5. In a bag, separable members permanently joined at their upper portions and capable of separating movement at the other portions thereof, and an interior lining and an exterior cover individually secured to the lower parts of the separable members, said separable members adapted to spread and distribute the strains and stresses of a filled bag, to remove such strains and stresses from the frame and closure of the bag.

In testimony that I claim the foregoing as my invention, I have signed my name hereto.

JACOB RITTER.
